UNITED STATES PATENT OFFICE.

ALFRED E. HORMAN, OF NEW YORK, N. Y.

POWER HAMMER.

Application filed March 18, 1924. Serial No. 700,127.

This invention relates to a power hammer and means to operate the same.

One object of the invention is to provide an improved means for operating the hammer to control without fatigue to the operator the force and frequency of the blows or stop the hammer in any of its operating positions.

Another object is the provision of a simple but efficient mechanism to shift the hammer either way along the anvil without stopping the hammer, the control for such shifting mechanism being preferably associated with the first mentioned controlling means so that the operator may readily change the force of the blow and the position of the hammer simultaneously or independently at will.

Another object lies in the provision of reliable automatically operating mechanism to disconnect the shifting means when the hammer reaches either end of the frame so that the hammer cannot overtravel.

Another object is to provide a device of the character referred to which can be operated at a high speed.

Another object is to provide releasable means for the hammer so that the hammer head may be moved back out of the way and the anvil used without it.

In the drawings forming a part of this specification and illustrating one embodiment of this invention,

Fig. 1 shows in elevation one side of the machine.

Fig. 2 is an elevation of the other side of the machine.

Fig. 3 is a front elevation.

Fig. 4 is a section taken on the line 4—4 of Fig. 3.

Fig. 5 is a section on the line 5—5 of Fig. 4; and

Fig. 6 is a section on the line 6—6 of Fig. 4 looking in the direction of the arrows.

The machine is provided with a base 1 which carries the frame 2 supporting the movable parts of the machine. Mounted upon one end of the base is an anvil support 3 to which is detachably secured an anvil 4. Power to operate the device is furnished by the constantly rotating power wheel 5 connected by belt 6 to the power wheel 7. In order to vary the effective connection between the two power wheels, the idler pulley 9 operating as a belt tightener is provided. This pulley is mounted upon a bell crank

lever 8 provided with an operating arm 10. Forward or rearward movement of the arm 10 will vary the degree of tightness of the belt allowing more or less slippage between the belt and the power wheels. A brake shoe 12 for the power wheel 7 is carried by the bell crank lever 13 pivotally mounted eccentrically of the axis of the wheel. The mechanism for controlling the operation of the arm 10 and lever 13 will be described hereinafter.

Mounted transversely on the frame is the main supporting bar 14 and a guide 15. Slidably supported on this bar and guide is the bifurcated frame 16 which guides and controls the transverse movements of the hammer. The hammer head proper 18 is pivotally connected to the outer or free end of supporting arm 19, as indicated at 20. A positioning arm 21 is pivoted to the head at a different point thereon as indicated at 22. This second mentioned arm is, as shown formed with a sleeve 23 from which project arms 24 extending along opposite sides of arm 19.

A pin or bolt 25 supported by the arms 24 supports a filler block 26 and rollers 27. The rollers engage with the cams 17 carried by the frame 16. A spring 28 is mounted in a slot 29 in the supporting arm 19 between the filler block 26 and the bolt 30. The latter serves as a means for adjusting the compression of the spring. The spring 28 presses the rollers into contact with the cams 17 and owing to the shape of these cams the positioning arm 21 which moves with the rollers maintains the hammer head 18 always in substantially vertical position. The construction and operating of the hammer supporting structure is described in my Letters Patent of the United States No. 1,457,168, dated May 29, 1923.

For raising the hammer head, I provide crank arms 31 and 32 pivotally supported by the cross bar 14 and supporting at their free ends the cross bar 33. This cross bar passes beneath the arm 19 and is detachably secured thereto as by means of link 34 pivotally connected to the said arm as shown at 35. The link 34 is detachably connected to arm 19 at 36. By disconnecting the link 34 at 36, the hammer head is free to swing upward and backward about the bar 14 into an inoperative position so as to permit use of the anvil without the hammer head 18 and without obstruction therefrom.

To provide a connection between the swinging cross bar 33 and the power wheel 7, block 39 has secured thereto, as by bands 38 and 38' springs 40 which are respectively connected by pairs of links 41 and 42 to the respective collars 43 and 44 slidably mounted on shaft or rod 45. The collars 43 and 44 are adjustably held in position on rod 45 by means of the cooperating nuts 46 and 47. An eccentric pivotal connection 48 is provided between the power wheel 7 and the center of the block 39. The rod 45 passes freely through the block 39 and is pivotally connected to the arm 31 as indicated at 49. This power transmitting structure just referred to allows for some resiliency or yielding between the power wheel 7 and the hammer so as to absorb in the power transmission shocks due to the blows of the hammer. The adjustable nuts 46, 47 furthermore allow adjustment of the tension of the springs and also of the position of the rod 45 longitudinally relatively to block 39 and consequently the position of the hammer relatively to the anvil.

For operating the arm 10 of the mechanism for controlling the application of power to the hammer head, a longitudinal bar 50, arranged on one side of the frame, is pivotally supported at one end by the operating arm 10 and between the ends thereof is supported by a link 51 substantially parallel to the arm 10. A corresponding bar 52 on the other side of the machine is pivotally supported by the brake lever 13 and by the link 53 parallel to the downwardly extending arm of the brake lever. These longitudinal bars are connected beyond the anvil end of the frame by the cross connecting rod 54. All of the pivots of this supporting structure are sufficiently loose to allow free movement of the bars 50 and 52 and their supporting links and arms. A spring 55 attached to the link 51 is adjustably connected with the frame as indicated at 56. This spring tends to hold the longitudinal bars 50 and 52 in position to loosen the belt so that the hammer head remains stationary and to apply the brake. A platform or pedal 57 is mounted for vertical oscillation about the rod 54. Forward or rearward movement of the platform or pedal affects tightening or loosening of the driving belt and at the same time the releasing or application of the brake. For facilitating such movement of the platform or pedal, the latter is, as shown, provided at its front and rear edges with flanges against which the foot of the operator may be caused to bear. The mechanism for controlling the lateral movement of the hammer head includes a substantially horizontal rod 58 passing slidably through a guide 59 on the platform or pedal and pivoted to the upright link 60 passing loosely through the guide 61 on the

frame. The tilting of the platform 57 will accordingly raise or lower the upright link 60, this movement not being materially affected by forward or rearward movement of the platform. A lever 62 is keyed as indicated at 63 to a rotatable rod 64 extending transversely of the frame. The counter-weight 65 on the lever 62 balances the weight of the linkages just referred to. A connection such as an arm 66 is joined to the lever 62. A tension spring 67 is secured at its opposite ends to the arm and to the frame. The arm 66 and spring 67 tend to hold the lever 62 normally in its intermediate position.

Mounted slidably but non-rotatably on the rotatable rod 64 and confined against lateral movement with respect to frame 16 between the bifurcated parts thereof is a yoke shaped latch member 68. The latch member is provided with inner clutch fingers 70 and with outer projections 71. The inner fingers are arranged to engage either the upper or lower section of a constantly moving endless chain 72 rotating on sprocket wheels 73 and 73^a. Sprocket wheel 73 is secured on shaft 74 driven by the worm gear 75 meshing with the suitable worm 76 secured to the supporting shaft for the constantly driven wheel 5 and rotating with said wheel.

By tilting the pedal or platform 57 about the axis of the longitudinal rod 54, it is possible to tilt lever 62 against the tension of spring 67 and accordingly to engage or disengage either the upper or lower finger 70 with the adjacent section of the endless chain 72. The chain 72 always runs in the same direction and at relatively low speed, so that engagement of the fingers 70 therewith and disengagement of the fingers therefrom can be readily effected. With this construction, the hammer may be run at a high speed, there being no high speed parts to be engaged or disengaged. Suitable means, such as cams or stops 77, are provided at the sides of the frame to engage the outer projection 71 of the yoke shaped member to automatically disengage said member from the endless chain 72 as the former approaches either side of the frame. A suitable guide 78 is preferably provided between the chain sections to prevent undue sagging thereof.

In operation, power is supplied to rotate the wheel 5 at substantially constant speed. The transmission of power from the wheel 5 to the power wheel 7 is controlled by the operator moving the platform 57 in a substantially horizontal, or forward and rearward, direction toward or away from the machine. Forward movement of the platform 57 by the foot of the operator towards the anvil causes the belt to be tightened and power to be applied to reciprocate the hammer head up and down, the brake 12 being moved to inoperative position. Positioning

of the platform 57 in its extreme outward position applies the brake 12 and stops the power wheel 7 (and consequently the hammer) in any position. The spring 55 tends 5 to automatically move the parts to this position. Transverse movement of the hammer along the frame can be obtained at any time by tilting the platform or pedal 57 so as to engage either the upper or lower projections 67 with the adjacent section of the constantly moving endless chain 72. As the upper and lower portions or sections of the chain move in opposite directions, they carry the hammer head along the anvil in one 10 direction or the other depending upon which of these chain sections is engaged by the latch projection 67.

By the construction shown the operator has the position and force of the hammer under 20 his absolute control at all times. If he should carelessly leave the machine running it is automatically stopped by the functioning of the spring 55. If he should leave the latch 68 in engagement with the chain while 25 operating the hammer or otherwise the latch will be automatically disconnected when the hammer reaches the end of its range of transverse movement. The operator may safely rest part of his weight on the platform 30 57 without affecting the operation of the machine as it requires either a horizontal traveling motion or a tilting motion of the platform to influence the hammer. This is an important feature of the invention in 35 that it avoids fatigue on the part of the operator and is of great value when a considerable amount of light work is being done.

While a specific embodiment of this invention is shown in the drawings, it is obvious 40 that changes may be made in the same without departing from the spirit of the invention so long as they fall within the scope of the appended claims.

Having thus described my invention, what 45 I claim as new and desire to secure by Letters Patent of the United States is:

1. A power hammer comprising a hammer head, a support therefor, means to operate the hammer with a variable force to its 50 blow, and means to shift the hammer head transversely with respect to the support, said operating and shifting means having a common control means to permit simultaneous transverse positioning of the hammer head and selective regulation of the force of the hammer blow.

2. A power hammer comprising a hammer head, a support therefor, means for operating the hammer head in an up-and-down 60 direction with a variable force to its blow, means for feeding the hammer head laterally with respect to the support, and means including a common operating member to control the operation of said operating and 65 feeding means to permit the simultaneous

transverse feeding of the hammer head and selective regulation of the force of the hammer blow.

3. In a power hammer, the combination of an anvil, a hammer head, means to operate 70 the hammer head with a variable force to its blow, means to shift the operating position of the hammer head along the anvil and controlling mechanism for said operating and shifting means including a single operating 75 member arranged to tilt and to move bodily to permit simultaneous transverse shifting of the hammer head and selective regulation of the force of the hammer blow.

4. In a device of the class described, the 80 combination of a hammer head, an anvil, means to operate the hammer head with a variable force to its blow, means to shift the operative position thereof along the anvil, and control means common to both 85 said means comprising a single bodily shiftable and independently tilttable pedal to permit simultaneous transverse positioning of the hammer head and selective regulation of the force of the hammer blow. 90

5. The combination of a tool, and means to shift the operating position of the tool comprising an elongated flexible endless member constantly moving longitudinally thereof and means connected with the tool 95 and arranged to engage the endless member.

6. The combination of a tool, means to shift the operating position of the tool comprising a flexible endless member constantly moving longitudinally thereof, means connected with the tool and arranged to engage the member, means tending to hold the engaging means in neutral position, and means for moving the engaging means to operative 100 position. 105

7. The combination of a tool, means to shift the tool laterally comprising a constantly moving endless flexible member having sections moving simultaneously in opposite directions, and means connected with the tool and arranged to be connected with either of the two oppositely moving sections of the member to shift the tool in either direction. 110

8. The combination of a tool, means to shift the position of the tool comprising an endless chain and pivoted latch members connected with the tool and arranged to engage either of two oppositely moving chain sections. 115

9. The combination of a tool, means to shift the position of the tool comprising an endless chain, a transverse shaft, a latch slidably but non-rotatably mounted on the shaft, and means to rotate the shaft whereby 120 to engage or disengage the latch and the chain.

10. The combination of a tool, means to shift the position of the tool comprising an endless chain, a transverse shaft, a latch 125

slidably but non-rotatably mounted on the shaft, and means to rotate the shaft whereby to engage or disengage the latch and the chain, said last mentioned means comprising 5 a tiltable controlling member.

11. The combination of hammering means, a supporting frame therefor, means on the frame to support and guide the hammering means for transverse movement, means to shift the hammering means along the transverse members, and automatic means to render the shifting means inoperative as the hammering means approaches either side of the frame, said automatic means including 10 stationary cams mounted on the frame.

12. The combination of hammering means, a support for the same comprising a guide, means to move the hammering means along the guide comprising a shifting member carried by the support and movable longitudinally of the guide and a cooperating member connected with the hammering means and adapted to engage or be disengaged from the shifting member, means operable 20 by the operator to control the engagement of said members, and automatic means to effect the disengagement of said members as the hammering means reaches a predetermined point in its movement across the 25 frame.

13. In a power hammer, the combination of an anvil, a hammer head, means including a belt for operating the hammer head up and down, means including an elongated

constantly moving feeding member having 35 portions moving in opposite directions and a clutch member movable into engagement with said feeding member for shifting the hammer head along the anvil in either direction, controlling mechanism for said clutch member including a pedal operatively connected with said member, and controlling mechanism for said operating means including a belt tightener co-acting with said belt, and a movable operating member connected with said tightener, said pedal being tiltably mounted upon said operating member for effecting movement of said clutch member. 40

14. In a power hammer, the combination of an anvil, a hammer head, means including a belt to operate the hammer head up and down, a movable tightening member co-acting with said belt, means including a feeding device and a clutch member movable 45 into engagement therewith for shifting the hammer head along the anvil, and controlling mechanism for said clutch member and said belt tightening member, including a pedal, a movable support upon which said pedal is tiltably mounted and means whereby the tilting of said pedal operates one of 50 said members and the bodily movement thereof with said support operates the other member.

In testimony whereof, I have signed my 55 name to this specification.

ALFRED E. HORMAN.
